UNITED STATES PATENT OFFICE.

ALMON E. NORRIS, OF BROOKLINE, MASSACHUSETTS.

WINCH.

Original application filed March 31, 1921, Serial No. 457,271. Divided and this application filed April 13, 1922. Serial No. 552,400.

To all whom it may concern:

Be it known that I, ALMON E. NORRIS, a citizen of the United States, and a resident of Brookline, in the county of Norfolk and 5 State of Massachusetts, have invented an Improvement in Winches, of which the following description, in connection with the accompanying drawings, is a specification, like characters on the drawings representing 10 like parts.

This invention relates to winches, and aims to facilitate the dismounting of the mechanism, as well as to prevent the escape of oil from the interior thereof. The application 15 is a division of my prior application, Ser. No. 457,271, filed March 31, 1921, patented Jan. 20, 1925, No. 1,523,829.

The invention will be best understood by reference to the following description, when 20 taken in connection with the accompanying drawings of one illustrative embodiment thereof, while its scope will be more particularly pointed out in the appended claims.

In the drawing, the single figure shown is 25 a central, vertical, sectional view of a winch exemplifying the invention.

Referring to the drawing, and to the embodiment of the invention which is selected for exemplification, there is shown a winch 30 comprising a casing 4, presenting a base 6 surmounted by a winch head 8, to which a worm gear 10 is suitably secured, as by means of cap-screws 12. A worm 14, meshing 35 with the worm gear, drives the latter and thereby rotates a winch head, which is mounted to turn on upper and lower bearings 16 and 18, presented by a hollow column 20, upstanding from and conveniently formed as an integral part of the base 6. 40 The described gearing is intended to run in an oil bath contained in the casing.

The construction is such that the winch head and the worm gear may be removed as a unit, without the necessity of detaching 45 one from the other, this being rendered possible by providing the casing with a circumferential wall 22, encircling the worm gear and affording an annular chamber 24 having an entrance 26, whose diameter is greater 50 than that of the worm gear. The chamber, however, is normally closed, and the mechanism therein is protected against the entrance of foreign matter by providing the winch head with a part, herein a skirt 28, at 55 least as large in diameter as the entrance 26,

and preferably overlapping the latter, as clearly shown in the drawing. This skirt 28 and the wall 22 have confronting surfaces opposed end to end, and they are suitably constructed to exclude foreign matter, and 60 to prevent the escape of oil, as by providing them with interjacent parts, in the present example inner and outer depending flanges 30 and 32 on the skirt, presenting between them an annular groove 34, which receives 65 an upstanding flange 36 presented by the wall 22.

It has been found that the best results are secured by providing the depending flange 30 with a beveled surface 38, and by providing the flange 36 with a similar, but oppositely beveled, surface 40. The first bevel tends to prevent the oil from creeping up into the joint presented by the adjacent surfaces of the flanges 36 and 30, while the second bevel forms an enlarged space or chamber, which tends to break the adhesion of the oil, and to allow the latter to gravitate back into the casing. The cooperative effect 75 of the bevels is to eliminate all leakage of 80 oil at the joint. Thus, the described construction permits the parts to be easily and quickly dismounted, without the necessity of detaching the worm gear from the winch head, while at the same time affording 85 proper protection for the driving mechanism from foreign substances, and preventing the escape of lubricant.

Having thus described one embodiment of my invention, but without limiting myself 90 thereto, what I claim and desire by Letters Patent to secure is:

1. In a cable winding apparatus, the combination of a cable winding spool and a base presenting a chamber, and driving means housed in said chamber, said spool and base being provided with means to prevent the escape of oil at the joint between them, the last-mentioned means including concentric annular parts one of which presents a beveled edge within said chamber.

2. In a cable winding apparatus, the combination of a cable winding spool and a base presenting a chamber, and driving means housed in said chamber, said spool and base being provided with means to prevent the escape of oil at the joint between them, the last-mentioned means including two annular parts one of which presents an annular groove and the other an annular projection 110

entering said groove, said parts presenting closely adjacent confronting surfaces, said projection entering the groove to an extent which leaves a chamber larger than the space between said confronting surfaces.

3. In a cable winding apparatus, the combination of a cable winding spool and a base presenting a chamber, and driving means housed in said chamber, said spool and base being provided with means to prevent the escape of oil at the joint between them, the last-mentioned means including two annular parts one of which presents an annular groove and the other an annular projection, the latter presenting a beveled end.

4. In a cable winding apparatus, the combination of a cable winding spool and a base presenting a chamber, and driving means housed in said chamber, said spool and base being provided with means to prevent the escape of oil at the joint between them, the last-mentioned means including two annular

parts one of which presents an annular groove and the other an annular projection, 25 the latter presenting an inwardly facing beveled surface.

5. In a cable winding apparatus, the combination of a cable winding spool and a base presenting a chamber, and driving means 29 housed in said chamber, said spool and base being provided with means to prevent the escape of oil at the joint between them, the last-mentioned means including two annular parts one of which presents an inner, annular part exposed within said chamber and having an inwardly facing beveled end and presenting also an annular groove outwardly beyond the inner annular part, and the other annular part being received in said 40 groove and presenting an inwardly facing beveled end.

In testimony whereof, I have signed my name to this specification.

ALMON E. NORRIS.
